FIG.1

FIG.2

FIG. 1 is a front perspective view of a building structure showing my new design; and

FIG. 2 is a front perspective view of a modification of the building structure shown in FIG. 1.

The other side of the structure not shown is the same as the side shown in FIGS. 1 and 2 and the top and rear are essentially plain.

The characteristic feature of my design resides in the front facade.

This is a division of application Ser. No. D. 20,041, filed Nov. 12, 1969, which has matured into Pat. No. D. 221,140, issued July 13, 1971.

I claim:

The ornamental design for a building structure, substantially as shown and described.
